PIPE CUTTING MACHINE

Sherman C. Twigg and George D. Major, Cumberland, Md., assignors of one-tenth to William E. Bowman, Alexandria, Va.

Application March 21, 1932, Serial No. 600,276.

5 Claims. (Cl. 266—23)

The invention relates to machines for cutting pipes of varying sizes in planes at any predetermined angle to the longitudinal axes of the pipes to facilitate the formation of elbows, by welding or otherwise connecting the beveled ends of the pipes, and also to expedite the cutting of pipes in desired lengths, by means of a cutting flame, such, for example, as that produced by an oxyacetylene blow torch, said machine including means for rotating the pipe about its longitudinal axis and means actuated by the rotating pipe to cause the cutting flame to follow a predetermined zone of contact with the surface of the tube.

The invention is illustrated in the accompanying drawings, in which:—

Fig. 1 is a plan view of the machine.

Fig. 2 is a side elevation partly in section.

Fig. 3 is an end elevation.

Fig. 4 is an enlarged fragmentary perspective view of the means for indicating the angle of the cut.

Fig. 5 is an enlarged section on line 5—5 of Fig. 1.

Fig. 6 is a detail of the slotted yoke crank motion.

Fig. 7 is an enlarged section on line 7—7 of Fig. 1.

Referring to the drawings, 1 indicates a suitable base upon which the entire mechanism is mounted and is of a character to admit of the apparatus being readily transported by hand, or mounted upon a truck, so that it may be located conveniently to the work.

Supported on pivots 3 mounted on one side and at opposite ends of the base 1 are standards 2 connected by a cross piece 4, said parts constituting a tilting frame adapted to be swung into and out of perpendicular relation with respect to the base, as indicated in full and dotted lines in

Fig. 3. Mounted for perpendicular adjustment on the standards 2 are bracket-like supports, each comprising a normally horizontal bar 5 provided with a clamping yoke 6 engaging one of the standards and secured in adjusted position by bolt and nut 7, each rod being braced by a strut 8 connected to a collar 10, slideable on the standard and connected to the corresponding yoke 6 by brace 9, the two collars 10 being connected by cross brace 10'; the parts so assembled forming a rigid frame adjustable to different heights above the base and constituting a firm support for the cutting torch and the operating and controlling mechanism associated therewith.

Adjustable longitudinally of each bar 5 is a generally U-shaped frame 11, the upright mem-

bers of which are provided with holes or bores engaged by the bar, one member being slotted and fitted with a wing bolt 11' by means of which the frame is clamped in adjusted position to the bar. Welded to upright members of the frames 11, 11 are parallel tracks 12, 12 extending beyond the base 1 at one end of the machine, and connected at their extended ends by cross bar 13.

Welded to the frames 11, 11 are parallel bars 15, 15, between the mid sections of which is secured a cross bar 16 carrying a center bearing stud 17 partly countersunk in the cross bar and secured in position by set screw 18, said stud forming the support for an antifriction bearing 19, which, in turn, forms the pivotal support for a friction disk 20.

Mounted below the friction disk 20, with one end hinged to a bracket 23 secured to cross bar 16 and its other end engaging a vertically elongated bearing slot 22 in one of the U-frames 11 is a shaft 21, upon which is slidably and rotatably mounted a friction wheel 24 adapted to be engaged with the under face of the friction disk 20, when the outer end of shaft 21 is lifted by the engagement of the wheel 24 with the pipe to be cut, as will be explained hereinafter. Wheel 24 is rotatably connected to a collar 26, to which is hinged one end of a bar 25, the other end of which is provided with a clevis or yoke 27 engaging laterally projecting pins on nut 28 mounted on screw shaft 29 journaled for rotation only in bracket 30 secured to cross bar 16 and in a bearing in yoke 11, the outboard end of the screw shaft having an operating head 29' fixed thereto. The bar 25 is provided with scale markings, preferably in inches, and cooperating with the scale is an index finger or pointer 32 secured to cross bar 16 in alignment with the center of friction disk 20.

Fixed diametrically to the upper face of friction disk 20 is a cross bar 30' on which is slidably mounted a pin 35 adapted to be clamped in adjusted position to the rod by eye-bolt 32 and wing nut 34, as particularly shown in Fig. 6. Pin 35 engages an elongated slot in a cross yoke 40 fixed to the end of a carriage mounted on rails 12, 12. Disk 20, adjustable pin 35 and yoke 40, therefore, constitute a slotted yoke crank motion for converting the rotary motion of the disk into reciprocatory motion of the yoke 40 and the carriage to which it is connected, the extent of the reciprocation of the carriage being regulated by the distance of the pin 35 from the center of the disk 20.

The carriage aforesaid comprises parallel bars

- 41 and cross bar 42, the outer end of each bar 41 being turned downwardly to form extension 41'. The ends of the respective cross bars on opposite sides of the carriage are finished with yokes 43 in which are journaled traction wheels 44, 44 having grooved peripheries engaging the rails 12, 12. Two complementary traction wheels 46, 46 are journaled in the yoked outer ends of levers 45, 45 pivoted at 47 to the side bars 41 of the carriage, the inner ends of said levers 45 being connected by a helical spring 48. This arrangement of the various traction wheels insures an effective mounting for the carriage on the rails 12, permitting free movement of the carriage without tendency to bind or jam between the rails.
- Fixed to one rail 12 is a sleeve 51 in which is adjustably mounted a rod 50 which is clamped, in its adjusted position, to the sleeve by set screws 52, said rod having scale markings thereon to indicate the adjustment of the machine to the diameter of the pipe, expressed in inches. The lower end of the rod 50 is bent at a right angle and pivoted thereto is a rod 53, which slides freely in a sleeve 54 fixed to a pintle 55 journaled in the lower end 41' of adjacent side member 41 of the carriage, and fixed to the end of pintle 55 is a crank arm 56, to the outer end of which is fixed one end of a cross bar 57, the other end of which is secured to a crank arm 58 pivoted at its lower end to a pin 59' carried by the end 41' of the other side member 41 of the carriage, the pintle 55 and pin 59' being in axial alignment. The end of the latter side member 41 is formed as a sector-shaped frame 59 having a scale 60 thereon graduated in degrees, with which scale the upper end of crank arm 58 cooperates to indicate the angular inclination of the cut to be made in the pipe with reference to the longitudinal axis of the pipe.
- Fixed to the cross bar 57 is a nozzle or head 61 for applying the cutting flame to the pipe. As conventionally illustrated, the nozzle or blow torch 61 is of the type employing an admixture of oxygen and acetylene as the heating agent and a jet of oxygen as the cutting agent. As this type of blow torch is well known, a more detailed description of the same is not necessary. The supply of oxygen and acetylene to the three nipples 62 of the torch or head 61 is controlled by any suitable valve mechanism usually employed for this purpose, but, as a matter of convenience, the control valves are mounted on the cross brace 4 connecting the upper ends of the standards 2, the said cross brace being provided with two transverse bores into which are tapped the threaded ends of control valves 64 and 65 adapted to be connected by piping to the tanks carrying the oxygen and acetylene, the other ends of the bores being provided with nipples 63, which are connected by flexible tubing to the corresponding nipples 62 in the head 61. Control of the cutting jet of oxygen is effected by means of a separate valve diagrammatically illustrated in Fig. 7, which controls a by-pass 68 from the main oxygen valve 64 to the nipple 63, which is connected to the corresponding nipple 62 on the head 61, the valve comprising a spring seated valve disk 67, valve stem 66 projecting above the bar 4 and operated by a pivoted lever 65'.
- The pipe to be cut is mounted directly on the base and is rotated on its longitudinal axis during the cutting operation. The mounting for the pipe comprises two or more pairs of rollers 75, 76 mounted on longitudinal shafts 73, 74, journaled in open bearings, such as 71, 72, formed in

the flanged projections 70 on the upper face of the base. As illustrated, there are two pairs of rollers, which are sufficient to support the pipe during the cutting operation, the rollers 76 being fixed to shaft 74, which latter is journaled in the open bearings 72 at opposite ends of the machine. The two rollers 75 are mounted on shaft 73, which is selectively journaled in any of the coordinate open bearings 71, so that the two sets of rollers may be adjusted relatively toward and from each other to accommodate pipes of different diameters.

The pipe is positively rotated by frictional engagement with the set of rollers 76, which, in turn, is driven by any appropriate gear mechanism, which latter may be operated either manually or by a motor. For machines adapted to cut pipes of smaller sizes, up to ten inches in diameter, the power necessary to operate the machine, which is preferably manual, comprises a shaft 80 having an operating crank on its outer end, said shaft being journaled in bearings carried by the base and having mounted thereon a gear 81, which meshes with a similar gear 82 fixed to shaft 83, which carries a worm 84 meshing with worm gear 85 on a short transverse shaft, which carries a pinion 86 meshing with gear 87 fast to shaft 74.

The operation of the machine, as described, is as follows:

The machine is first set to accommodate the particular size or diameter of the pipe to be cut. Shaft 73 is adjusted to or from shaft 74 to properly space the sets of rollers 75, 76 to afford a firm support for the pipe. Friction wheel 24 is adjusted on its supporting shaft 21 a distance from the center of disk 20 equal to half the diameter of the pipe, as indicated by the scale on the bar 25, this adjustment being effected by operating the feed screw 29. The supporting brackets are then adjusted perpendicularly on the standards 2 and clamped in their adjusted position by the wing-nuts 7, and the frame, comprising the parallel tracks 12, 12 and their connections with the horizontal rods 5, 5 of the brackets, is adjusted and clamped in position on said rods, so that the nozzle axis of the torch 61 will be in vertical alignment with the longitudinal axis of the pipe, the elevation of the carriage and, therefore, of the nozzle being determined by the scale markings on the rod 50. Crank pin 35 is released from its locked relation on the cross bar 30 by backing off the wing-nut 34, so that the crank pin may slide freely on said bar. Rod 53 is then swung to perpendicular position, its pivotal point being in horizontal alignment with the center of the pipe. This swinging movement of the rod or lever 53 causes a partial rotation of the crank arms 56 and 58, thereby moving the head of the torch, which is fast to cross bar 57, to bring the nozzle of the torch to perpendicular position with respect to the longitudinal axis of the pipe, which position will be indicated by the pointed end of crank arm 58 standing opposite the zero marking on the scale 60. This movement of the lever 53 will also cause the carriage, including the side bars 41, 41 and the slotted link 40, to move rearwardly, thereby rotating the friction disk 20 until the cross bar 30 is at right angles to the longitudinal axis of the pipe and the crank pin 35, which is freely slidable on the rod 30', moves into position in vertical alignment with the center of the disk 20. Lever 53 is then swung on its pivot to bring the index end of crank arm 58 to the marking on the scale 60 to indicate the angle of cut to be made in the pipe with respect to the longitudinal axis of 150

the latter. This will cause the nozzle of the torch to assume the position with its longitudinal axis parallel with the crank arm 58. The swinging movement of the lever 53 causes the frame and 5 the slotted link 40 to move in the same direction, thereby causing the crank pin 35 to slide on the cross bar 30 and effect a partial rotation of the disk 20 until the cross bar 30' assumes an angular position with respect to the longitudinal axis of 10 the pipe equal to the angle of the cut to be made. The crank pin 35 is then clamped to the cross bar 30'. In order to place the pipe in position to be cut, the standards 2 and the mechanism carried thereby are swung to the dotted position indicated 15 in Fig. 3. When the pipe has been properly positioned on the rollers 75 and 76, the standards 2 are swung back to perpendicular position and the friction wheel 24, engaging the highest point of 20 the pipe, will be moved into engagement with the under face of friction disk 20, this movement of the friction wheel being permitted by reason of the engagement of the end of its supporting shaft 21 with the elongated bearing 22'. The supply 25 of oxygen and acetylene is then turned on at the valves 64 and 65 and ignited to direct a heating flame against the surface of the pipe at a point where the cut is to be initiated and, when this localized area of the pipe has been heated to a sufficient degree, a supply of oxygen for the cutting 30 jet is turned on by depressing the handle 65 of the valve controlling the by-pass from the main oxygen valve 64 and, at the same time, the hand crank 80 is operated to rotate the pipe at the proper speed to effect a clean cut by the oxygen 35 jet. The rotation of the pipe produces a coordinate rotation of the friction disk 20 through friction wheel 24 and this rotation of the friction disk causes the crank pin 35 to traverse the slot in the yoke 40 and thereby cause the carriage to 40 reciprocate on the tracks 12, one complete rotation of the pipe effecting a complete rotation of the friction disk, which produces the complete oscillation of the cutter head 61 and the cutting jet in a plane including the longitudinal axis of the 45 pipe. This swinging movement of the torch produces a clean circumferential cut through the walls of the pipe, so that all parts of the surface of the pipe end will be in a common plane and will make a flush contact with the cut face of the 50 mating pipe section, which would not be the case if the axis of the torch nozzle were maintained perpendicular to the axis of the pipe during the entire cutting operation.

What we claim is:

55 1. A pipe cutting machine, comprising means for supporting and rotating the pipe about its longitudinal axis, an adjustable cutter, and

means operated by and through the rotation of the pipe for reciprocating the cutter in a plane including the longitudinal axis of the pipe and oscillating the cutter in said plane through an arc equal to the angle of inclination of the desired cut with reference to said longitudinal axis. 80

2. A machine for cutting pipe, comprising means for mounting and rotating the pipe, a cutter, and means actuated by the rotating pipe for simultaneously reciprocating and oscillating the cutter in a plane including the longitudinal axis of the pipe and through an angle equal to the angle of the cut relative to said axis. 85

3. A pipe cutting machine, comprising a base, parallel sets of rollers thereon to support the pipe to be cut, means for driving one set of rollers to rotate the pipe on its longitudinal axis, a frame supported above the base, a carriage slideable on said frame, a crank shaft journaled transversely of the carriage, a cutting torch fixed to said crank shaft, a rock lever pivoted to said frame and connected to said crank shaft to effect swinging movement of the torch coordinate with the reciprocation of the carriage, and a slotted yoke crank motion connected to the carriage and actuated by frictional engagement with the rotating pipe for reciprocating the carriage. 90

4. A machine as described in claim 3, in which the slotted yoke crank motion comprises a slotted yoke mounted transversely of the carriage, a friction disk carrying a crank pin engaging the yoke, and a friction wheel adapted to engage the pipe and the friction disk and rotating the latter coordinately by and with the pipe. 105

5. A pipe cutting machine, comprising a base, parallel sets of rollers thereon to support the pipe to be cut, means for driving one set of rollers to rotate the pipe on its longitudinal axis, a frame supported for perpendicular and transverse adjustment relative to the base, a carriage slideable on said frame, a crank shaft journaled transversely of the carriage, a cutting torch fixed to said crank shaft, a rock lever pivoted to said frame and connected to said crank shaft to effect swinging movements of the torch coordinate with the reciprocation of the carriage, a slotted yoke mounted transversely of the carriage, a friction disk journaled on the frame and carrying an adjustable crank pin, a friction wheel slidably supported on said frame below the friction disk and adapted to engage the pipe and the friction disk and rotating the latter coordinately by and with the pipe, and means for adjusting the friction wheel radially with reference to the disk. 115 120 125
